US00D704165S

(12) **United States Design Patent**
Won et al.

(10) **Patent No.:** **US D704,165 S**
(45) **Date of Patent:** **** May 6, 2014**

(54) **REMOTE CONTROLLER**

(75) Inventors: **Dong-Hee Won**, Seoul (KR); **Yong-Joo Lee**, Seoul (KR); **Jun-Ho Yang**, Kyunggi-do (KR)

(73) Assignee: **Samsung Electronics Co., Ltd.**, Suwon, Kyunggi-do (KR)

(**) Term: **14 Years**

(21) Appl. No.: **29/418,465**

(22) Filed: **Apr. 17, 2012**

(30) **Foreign Application Priority Data**

Nov. 23, 2011 (KR) 30-2011-0049398

(51) **LOC (10) Cl.** **14-03**

(52) **U.S. Cl.**

USPC **D14/218**

(58) **Field of Classification Search**

USPC ..... D14/218, 455; D13/168; D21/566; D10/104, 106; 345/169; 348/14.05, 348/114, 211.99, 734; 340/825.24; 341/22; 455/92, 95, 128, 151.1–151.4, 352, 455/355, FOR. 121; 700/65

OTHER PUBLICATIONS

U.S. Appl. No. 29/349,413, Applicant: Kyoung-Hoon Kim, et al., entitled Remote Controller for Television Receiver.

(Continued)

Primary Examiner — John Windmuller

(74) *Attorney, Agent, or Firm* — Flynn, Thiel, Boutell & Tanis, P.C.

(57) **CLAIM**

The ornamental design for a remote controller, as shown and described.

DESCRIPTION

FIG. 1 is a top front perspective view of a remote controller showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIG. 3 indicate a portion of the remote controller which forms no part of the claimed design.

1 Claim, 3 Drawing Sheets
